UNITED STATES PATENT OFFICE.

EDWARD STEIN, OF NEW YORK, N. Y.

DESIGN FOR AN UMBRELLA-HANDLE.

SPECIFICATION forming part of Design No. 22,310, dated March 28, 1893.

Application filed February 4, 1893. Serial No. 461,069. Term of patent 3½ years.

To all whom it may concern:

Be it known that I, EDWARD STEIN, a citizen of the United States, residing at New York, county and State of New York, have 5 invented and produced a new and original Design for Umbrella-Handles, of which the following is a specification, reference being had to the accompanying drawings, in which—

The leading feature of my design consists 15 of an umbrella handle having an ornamentation representing a globe, an anchor and a scroll that embraces both the globe and anchor.

a, represents an umbrella handle provided with the band b. Upon this band there are represented a globe c, and an anchor d. A 20 scroll e, surrounds the globe with one end and the anchor with the other end. The band is furthermore embellished by a flower f, and leaves g.

What I claim is—

The design for umbrella handles, substantially as herein shown and described.

EDWARD STEIN.
